UNITED STATES PATENT OFFICE

HOWARD P. KLING, OF WESTFIELD, MASSACHUSETTS, ASSIGNOR TO MOORE AND KLING, INC., OF BOSTON, MASSACHUSETTS, A CORPORATION OF MASSACHUSETTS

FILLING STATION APPARATUS

Application filed January 29, 1930. Serial No. 424,366.

This invention relates to liquid dispensing apparatus, and particularly to a means associated therewith adapted to increase the safety in dispensing volatile oils such as gasoline, and has for its general object to provide a means to prevent an accumulation of excessive pressure within the pumping system between the foot or check valve, and the outlet valve.

10 A further object of the invention is to provide a device which may be readily adapted to an existing pumping system.

15 A further object of the invention is to provide a pressure relieving device which will by-pass the liquid which escapes during such relief of excessive pressure around the check or foot valve, and back to the interior of the tank.

20 A further object of the invention is to provide a by-pass built into the check or foot valve having a relief valve operable to open at a predetermined pressure.

25 A further object of the invention is to prevent the accumulation of dangerous pressure in a liquid dispensing system due to the expansion of the liquid with changes in temperature.

30 These and other objects and features will more fully appear from the following specification in connection with the accompanying drawing, and will be particularly pointed out in the claims.

In the drawing:

35 Fig. 1 is a general view of a liquid dispensing apparatus embodying a preferred form of the invention.

40 Fig. 2 is a view in cross section of a foot or check valve with a preferred form of the invention applied thereto.

45 Fig. 3 is a cross sectional view of a different type of valve having a modified form of the invention applied thereto.

In the construction of liquid dispensing systems of the type herein disclosed a dangerous pressure may accumulate within the

system due to a rise in temperature caused by climatic or other external conditions. The system to which the invention applies includes a foot or check valve situated preferably at the end of the suction pipe or may be located in the suction pipe at any convenient point, a valve preferably manually operable situated at the end of or near the end of the outlet or filling pipe, and a pump of the rotary type driven by an electric motor or other suitable source of power. The pump may be of the well known centrifugal type, or may be any type of pump which does not act to retain pressure within the outlet pipe between the pump and the outlet valve. Due to the requirements of safety when such systems are used for dispensing volatile oils such as gasoline, the pump as well as the other elements of the system must be liquid and gas-tight with relation to the atmosphere. It is the purpose of this invention to provide a means to relieve any excessive pressure which may accumulate in such a system due to the causes above suggested.

In order to give a more complete conception thereof a preferred embodiment of the invention is shown as applied to a gasoline dispensing apparatus such as that used along the highways. A centrifugal pump 1 is securely fastened to a base 2, and is directly connected to an electric motor 3 by means of a shaft 5. A packing gland prevents leakage of the liquid from the pump along the shaft 5. The pump 1 has an outlet pipe 6 which connects with a flexible hose or filler pipe 7 having a manually operable valve 8 therein by means of which the flow of gasoline is controlled. The manually operable valve is preferably situated at the end of the filler pipe, and is preferably of the type disclosed by United States Patent No. 1,722,985. When the valve 8 is closed, and the motor shut off, no liquid can flow out of the filler pipe 7. In order to measure the quantity of liquid dispensed, a suitable me-

ter such as the flow meter 9 is inserted in the outlet pipe 6. The whole assembly is enclosed in a casing 10 through which the dial 11 is made visible to indicate the quantity of 5 gasoline dispensed.

A storage tank 12 is situated below the ground at some convenient point preferably a short distance removed from the pipe to permit the suction pipe 13 to assume an angular position. The suction pipe is connected at its upper end to the intake port of the pump, and extends to and projects into the tank 12 preferably to a point a short distance from the bottom thereof. A foot or 10 check valve 14 is connected to the lower end of the suction pipe to prevent back flow of the liquid. The valve 14 may be of any desired construction. As herein shown the valve consists of a double poppet gravity 15 closing type having a casing 15 within which are located two valve seats 16 and 17, one above the other and in series with relation to the flow of liquid. The sleeves 16 and 17 receive the valves 18 and 19 which are accurately guided to their seats by means of 20 the stems 20 and 21 which move vertically in guides 22 and 23. The lower end of the valve 14 is provided with openings 24 which are covered with filtering screens 25 to prevent 25 the passage of foreign matter into the system. A free passage of liquid is permitted upwardly, and any down flow is instantly checked by the valves 18 and 19 when the suction of the pump is discontinued. The 30 valve 14 may be located at any convenient point in the suction pipe such as the position indicated in dotted lines Fig. 1 just above the tank.

From the foregoing, it will be observed 40 that the whole system included between the foot or check valve 14 and the outlet or filler valve 8 is liquid and gas tight. Furthermore any pressure which exists in the system beyond the pump will be equal to the 45 pressure in the suction pipe with the exception of the slight effect of the difference in head due to the difference in elevation between the filler pipe and the suction pipe. This condition results from the fact that the 50 particular type of pump employed in such systems, as above described, when idle offers no substantial restriction to an equalization of pressure throughout the system. In fact since it is dangerous pressures which 55 may burst a filling hose or cause injury to other parts of the system and which are of a magnitude in excess of the maximum working pressure, such pumps can be said to offer no material resistance to an equalization 60 of excessive pressure throughout the system even when they are in operation. In operation, therefore, the valve 14 and the valve 8 retain a solid column of liquid having no outlet. If a rise of temperature occurs within 65 the liquid due to climatic or other con-

ditions, a dangerous pressure may accumulate between the valves, a condition which is not only dangerous but is usually forbidden by law.

In order to prevent such a condition the 70 present invention provides a means to bypass such pressure back to the storage tank 12. Such a by-pass may be inserted at any convenient point in the system. One desirable method is to provide a by-pass 27 leading 75 from the upper chamber 28 of the valve 14 to the lower chamber 29 which communicates with the tank 12. The by-pass may be constructed in any suitable manner such as by casting integral with the casing 15 of the 80 valve or may be fabricated of standard pipe fittings as herein shown. In the latter case a relief valve casing 30 is inserted into the by-pass assembly, and has mounted therein a spring-actuated relief valve 31 which opens 85 when an excessive pressure accumulates in the system by-passing the surplus liquid to the lower chamber 29 which reduces the excessive pressure to a value below or equal to a predetermined limit as determined by the spring 90 32, at which time the valve 31 will close.

Other methods of by-passing the fluid may be utilized. In Fig. 3 an elbow check valve is shown which may be inserted in the suction pipe 13 at a point occupied by the elbow 33, 95 in which case the elbow valve will take the place of and function in the same manner as the check valve 14. In the construction of the elbow valve a specially formed casing 34 contains a relief port 35 which leads from the 100 chamber 36 above the valves 37 to the chamber 38 below the valves. This relief port has a relief valve 39 therein which relieves excessive pressure in the system above the valve 32 in a manner similar to the relief valve 31. 105

In order to facilitate assembling of the valve 32 and to provide for adjustment of the relief valve 39 an opening 40 is formed in the casing 34 thereof. This opening is normally closed by a removable plug 41. 110

It is within the scope of the present invention to provide any suitable means to relieve excessive pressure within the system. For instance a relief valve may be inserted in the check valve itself or in the valve stem. 115

Having thus described the invention, what is claimed as new, and desired to be secured by Letters Patent, is:

1. A check valve for liquid dispensing systems adapted to be connected in series with the suction line thereof comprising a casing, an automatically closing valve therein acting to prevent back flow of liquid, chambers above and below said valve, a by-pass connecting said chambers, and a relief valve in said by-pass opened at a predetermined pressure to by-pass the liquid from the upper to the lower chamber. 125

2. In a liquid dispensing system, a check valve in the suction line thereof acting to 130

prevent back flow of liquid comprising a casing, a plurality of gravity closing poppet valves in series therein, a chamber above and below said valves, a by-pass connecting the chambers and a relief valve in said by-pass opening at a predetermined pressure to bypass the liquid from said upper to said lower chamber.

5 In testimony whereof, I have signed my name to this specification.

10 HOWARD P. KLING.
